CLAIM

The ornamental design for a bottle package, combination or substantially as shown.

DESCRIPTION

FIG. 1 is a front perspective view of a bottle package showing our new design;

FIG. 2 is a rear perspective view; and

FIG. 3 is a view taken substantially on the line 3—3 of FIG. 1 with only the carton portion of the bottle package being shown in section.

FIG. 1

FIG. 3
